UNITED STATES PATENT OFFICE

JAMES KEDEY, OF NEW YORK, N. Y.

IMPROVEMENT IN SECURING KNOB-ROSES TO DOORS.

Specification forming part of Letters Patent No. **152,999**, dated July 14, 1874; application filed April 25, 1874.

To all whom it may concern:

Be it known that I, JAMES KEDEY, of the city, county, and State of New York, have invented a new and useful Improvement in the Mode of Supporting the Rose-Plates of a Door or other Lock, of which the following is a specification:

In the accompanying drawing, Figure 1 is a vertical section, showing the mode of supporting the rose-plate of a mortise-lock. Fig. 2 shows a mortise-lock detached from the door, giving a side view thereof, showing the wood anchoring-bush confined between the plates of the lock.

Similar letters of reference indicate corresponding parts.

The invention consists in supporting the rose-plates of a door or other lock by a wooden bush arranged within the lock-case, as herein-after fully described.

A is the lock. B represents the door. C is

the rose-plate; C', the rose. E is the anchor-box. F is the wooden bush; D, the fastening-screw; H, the rose-socket. In Fig. 2 the bush is seen provided with the holes, so that a screw from each rose-plate may be inserted, or one from each side. There may be more than one bush-piece in the lock, so that two or more screws may be used if considered necessary, but for ordinary doors a spur, d, keeps the plate in place and answers all purposes.

Having thus described my invention, I claim as new and desire to secure by Letters Patent—

The wooden bush F inside a lock, substantially as and for the purposes described.

JAMES KEDEY.
